(57) **CLAIM**

The ornamental design for a drawer for refrigerator as shown and described.

DESCRIPTION

FIG. 1 is a front perspective view of a drawer for refrigerator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of the area ‘8’ as identified in FIG. 1; and,

FIG. 9 is a front perspective view showing the claimed design in an environment of use installed inside a refrigerator.

The unevenly spaced broken lines in FIGS. 1 and 8 are for purposes of annotating the enlarged view only and form no part of the claimed design; the broken lines depict portions of the drawer for refrigerator that form no part of the claimed
